(57) **CLAIM**

I claim the ornamental design for a nasal dilator, as shown and described.

DESCRIPTION

FIG. 1 is a front view of a first embodiment of my design for a nasal dilator;

FIG. 2 is a rear view of the design for a nasal dilator shown in FIG. 1;

FIG. 3 is a top view of the design for a nasal dilator shown in FIG. 1;

FIG. 4 is a bottom view of the design for a nasal dilator shown in FIG. 1;

FIG. 5 is a right side view of the design for a nasal dilator shown in FIG. 1; and,

FIG. 6 is a left sided view of the design for a nasal dilator shown in FIG. 1.
